DESIGN FOR A SHOE HEEL

James H. Stackhouse, Newton, and Winthrop Brown, Jr., Cambridge, Mass., assignors to The B. F. Goodrich Company, New York, N. Y., a corporation of New York

Application November 20, 1944, Serial No. 116,450

Term of patent 14 years

(Cl. D7—5)

To all whom it may concern:

Be it known that we, James H. Stackhouse and Winthrop Brown, Jr., citizens of the U. S. A., residing at Newton and Cambridge, in the county of Middlesex and Commonwealth of Massachusetts, respectively, have invented a new, original, and ornamental Design for a Shoe Heel, of which the following is a specification, reference being had to the accompanying drawing, forming a part thereof.

In the drawing:

Fig. 1 is a plan view of a shoe heel embodying our new design.

Fig. 2 is a section taken on line 2—2 of Fig. 1.

We claim:

The ornamental design for a shoe heel, as shown.

JAMES H. STACKHOUSE.
